METHOD AND APPARATUS FOR TREATING
CRUDE OIL

Gustav de Bretteville, Venice, Calif.

Application October 14, 1941, Serial No. 414,971

5 Claims. (Cl. 196—5)

This invention relates to methods and apparatus for treating crude petroleum or oil, as it comes from the well, and its general object is to provide a simple method for treating the oil to primarily prevent the escape of volatile gases therefrom, the method consisting essentially of bringing about a material decrease in the temperature of the oil before it is run to storage or a refinery, it being well known that crude oil issuing from the well may have a temperature up to 180 degrees Fahrenheit, and the temperature is generally increased by passing the oil through a dehydrator, consequently the oil retains a relatively high temperature under normal conditions, when reaching storage, thus resulting in the volatile gases that are suspended therein being expelled or liberated therefrom, especially in storage, but by the use of the temperature lowering and refrigerating steps of my method, the major portion of the gases are retained or preserved within the oil, thereby making it possible to produce a better grade of gasoline with less cost.

A further object is to provide an apparatus for carrying out my method, that is simple in construction, inexpensive to manufacture, and extremely efficient in use and service.

Another object is to provide an apparatus for the purpose set forth that includes means for cleaning the same and particularly for removing wax or the like therefrom, so as to allow free passage of the oil through the apparatus.

This invention also consists in certain other features of the method and construction of the apparatus, and in the combination and arrangement of the several parts thereof to be herein-after fully described, illustrated in the accompanying drawing and specifically pointed out in the appended claims.

In describing the invention in detail, reference will be had to the accompanying drawing wherein like characters denote like or corresponding parts, throughout the same, and in which:

The figure is a diagrammatic view of one form of apparatus for carrying out my method.

Referring to the drawing in detail, it will be noted that the apparatus in the form shown includes a dehydration unit made up of an upright cylindrical container or what I term a dehydration tank 1, that is connected with the usual gas trap not shown, the latter directly receiving the crude oil as it issues from the well. From the trap, the oil is directed to the tank by a pipe line that includes a pair of upright sections 2 and 3 connected together at their upper ends by a short section 4, and connected to the lower end of the

inner section 3 is a horizontal section 5 which extends into the tank for disposal diametrically thereof adjacent its bottom, and the section 5 is provided with a plurality of outlet openings 6 along the length of its upper surface, to allow passage of the oil into the tank, as indicated by the arrows.

The dehydration unit also includes a heater 7 for heating chemically treated water or solution, and rising from the heater is an outlet pipe line 8 which includes an upper portion 9 connected to the tank 1 substantially midway the height thereof, while an inlet pipe 10 to the heater extends from the lower end of the tank. By that construction, it will be obvious that the heated chemically treated water passes through the lower portion of the tank and is circulated between the latter and the heater to bring about separation of well water and foreign matter from the oil, so that the latter in a clean condition will rise above the normal water level within the tank, as shown.

The precooling unit for the oil includes a cylindrical upright receptacle 11 having upper and lower plates 12 and 13 fixed therein, the upper plate being disposed a considerable distance below the top wall of the receptacle, while the lower plate is arranged in close proximity to its lower end for cooperation with the upper plate to provide an oil receiving chamber. Secured to and disposed between the plates are water tubes 14, and the receptacle is in direct communication with the tank 1 through the medium of a pipe 15 that extends from the tank approximately at the normal level of the oil and is connected to the receptacle just below the upper plate 12.

Disposed in the space above the top of the receptacle and the upper plate 12 is a cold water spray nozzle of a diameter so that the water therefrom will be sprayed over the entire area of the plate 12, to assure that approximately the same quantity of water will pass through each of the tubes 14, and the nozzle is supported in close proximity to the top wall of the receptacle by a pipe line 17 which of course supplies water to the nozzle and from a suitable source of cold water supply. Suitably supported below the receptacle 11 in spaced relation thereto is a catch basin 18 having a concaved bottom and depending centrally therefrom is an outlet pipe 19, with the result it will be seen that an air space is provided between the receptacle and the catch basin, which tends to create a draft of air within the tubes, or in other words aerates the water, particularly as it passes through the lower portion

of the tubes, to bring about an increased cooling action of the oil.

From the precooling unit, the oil is passed to a refrigeration unit which also includes a cylindrical upright receptacle 20 having an oil inlet chamber 21 secured to and rising from the top wall thereof. Connected to the chamber 21 is the upper horizontal section 22 of a pipe line that also includes a vertical section 23 having a hand control valve 24 therein, and a lower horizontal section 25 extends between the vertical section 23 and the lower end of the precooling unit receptacle 20. The hand control valve 24 is disposed between the section 25 and the section 23, to close off the refrigeration unit from the precooling unit, and the vertical section 23 extends below the section 25 for connection with a lower horizontal section 26, the latter having connected thereto, an outlet section 27 for the receptacle 20 and which is secured to the bottom wall of the receptacle 20 in depending relation therfrom, as well as has a valve 28 therein for controlling the passage of oil from the receptacle 20 to the pipe section 26. A thermometer 29 may be secured to the section 26 to ascertain the temperature of the oil passing therethrough, as will be apparent.

Suitably supported in the receptacle 20 adjacent to the top wall thereof is a baffle plate 30 for distributing the oil over a refrigeration coil 31 mounted vertically in the receptacle 20, the coil having an inlet pipe 32 leading from a suitable refrigerating machine, and an outlet pipe 33 extending to said machine.

Secured to and rising from the lower horizontal pipe section 26 is an upright pipe section 34 that has its upper end connected to a gas bypass pipe that will be later described, to prevent a siphoning action taking place in the apparatus or system, and connected to the upright pipe section 34 is a horizontal section 35 that is disposed on the same level as that of the pipe 15, and the section 35 has an upright or vertical section 36 secured thereto and paralleling the lower portion of the pipe section 34, the section 36 having its lower end connected to an outlet section 37 that is connected to the section 26 through the medium of a valve 38, and the section 37 is connected to a pipe line that leads to a storage tank or the like for the oil. A valve 39 is provided for the section 37, and a valve 40 is likewise provided between the sections 26 and 34.

The upright pipe section 34 not only provides what may be termed a vent for the apparatus to prevent a siphoning action therein, as above set forth, but retards the flow of the oil through the apparatus, so as to keep the water tubes 14 covered with oil and receptacle 11 always full of oil and keep refrigeration coil 31 and the refrigeration receptacle 20 always full of oil at all times while the apparatus is in use.

In order to prevent the precooling unit from becoming gas locked, I provide a by-pass for the gas that conveys the same from the upper end of the section 2, to the inlet chamber 21, the by-pass including a pipe line 41 previously referred to and which extends from the section 2 to the chamber 21, and a pipe section 42 extends between the pipe line 41 and the pipe 15, for conveying any gas that may be in the oil as it passes from the dehydration tank 1 to the receptacle 11. Any gas that accumulates within the dehydration tank above the oil therein, is passed to the pipe line 41 by a pipe section 43, that extends from a partition 44 adjacent the top wall of the tank 1, 75

the partition acting to provide a cold water chamber 45, so that the gases condense when coming in contact with the partition.

From the structure so far described, and disclosure in the drawing, it will be obvious that crude oil from the gas trap, not shown, is passed to the upright section 2 and through the same as well as the sections 3 and 5, for disposal within the tank 1, to commingle with the chemically treated hot water therein, for removing water and foreign matter from the oil. The clean oil is then passed to the receptacle 11 through the medium of the pipe 15, where the temperature of the oil is reduced, prior to being acted upon by the refrigeration unit. From the receptacle 11 the oil passes through the pipe sections 25, 23 and 22, for disposal in the receptacle 20, where its temperature is materially lowered by the refrigeration coils 31. From the receptacle 20 the oil is passed to storage through the medium of the outlet section 27, and the pipe sections 26, 34, 35, 36 and 37.

A valve 47 is provided in the vertical pipe section 23, to prevent the oil from passing directly from the precooling unit to the pipe section 26, and the latter has an outlet valve or faucet connected to a reduced portion thereof, so that the oil can be tested either before or after it passes through the refrigeration unit.

It will be further obvious that the apparatus tends to become clogged with foreign matter, and particularly wax, paraffin or the like, and in order to clean the apparatus and to remove the foreign matter therefrom to allow free passage of oil therethrough, I provide a cleaning system which includes a motor driven pump 49 having a pipe line 50 connected at its lower end to the pump housing and at its upper end to the tank 1 above the transverse center thereof, the pipe line 50 having a valve 51 therein adjacent its upper end and the pipe line 50 is connected substantially midway its ends to the tank 1, by a valved coupling 52. A pipe line 53 has one end connected to the pump housing, and its opposite end is connected to the outlet section 37, between the valve 39 thereof and the upright section 36. A valve 54 is provided in the pipe line 53.

By that construction, it will be obvious that any suitable cleaning fluid can be pumped through the apparatus by reverse circulation, and after the apparatus has been thoroughly cleaned, the fluid is removed therefrom by pumping clean crude oil therethrough. The apparatus is then ready to be operated in the usual manner, to bring about the lowering of the temperature of the crude oil from the well, to prevent escape of the valuable and desirable volatile gases from the oil, so that the latter can be refined to yield gasoline of a better quality and at a lower cost.

It will be further noted from the drawing, that the pipe section 34 above the section 35 has a valve 55 therein and the vertical branch 56 of the gas by-pass pipe line 41, that leads to the inlet chamber 21, is also provided with a valve 57. A valve 58 is likewise provided in the pipe section 42 and the by-pass pipe line 41 is further provided with a valve 58' that is disposed just above the pipe section 2. The valves 55, 57, 58 and 58' are closed when the apparatus is being cleaned, to prevent the cleaning fluid from passing through the gas by-pass pipe line 41, as will be apparent.

In the event the oil is free from water and foreign matter as it comes from the well, it is of course not necessary to pass the same through the cleaning solution of the dehydration unit,

and that solution may be removed from the tank 1, but I prefer to pass the oil that comes from the well free from water and in a clean condition directly to the pre-cooling unit. For that purpose, I provide a by-pass pipe 59 that has its inlet end connected to the upright section 2 and its outlet end connected to the pipe 15, the latter having a valve 60 therein between the tank 1 and the pipe 59, and the section 2 is also provided with a valve 61 just above the inlet end of the pipe 59. A valve 62 is also provided in the by-pass pipe 59. By that construction, it will be obvious that it is not necessary to pass the clean oil through the dehydration unit and that it can be directly introduced within the pre-cooling unit.

While I have stated that my apparatus is connected to the usual gas trap in the production line from the well, to receive the oil after it passes through the trap, the apparatus may be connected ahead of the trap to refrigerate the oil before it reaches the trap, as in some instances, such arrangement will be desirable.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A method of treating crude oil to retain the natural volatile gases therein, consisting of conveying oil from a well gas trap in a vertical upward and thence downward course, introducing the oil from said course to the bottom of a dehydration unit for removing well water and other foreign matter therefrom, conveying the clean oil from the dehydration unit to the upper portion of a precooling unit, conveying the oil from the lower portion of the precooling unit to the top of a refrigeration unit, conveying the oil from the bottom of the refrigeration unit to storage, bypassing gases liberated from said oil in advance of the precooling unit to prevent the latter from becoming gas locked, and introducing the liberated gases into the top of the refrigeration unit to cause absorption thereof with the oil therein.

2. In an apparatus for treating crude oil, a dehydration unit including an upright tank,

means for circulating chemically treated hot water through the lower portion of the tank, a pipe line adapted for receiving oil as it issues from a well and including perforated means for introducing the oil into the lower portion of the tank for passage of the oil through the water to remove well water and foreign matter therefrom, a precooling unit having means of communication with the tank for receiving clean oil therefrom, a refrigeration unit having communication with the precooling unit for receiving the oil therefrom, and means for bypassing gases from the pipe line, tank and the communication means between the tank and the precooling unit for passing said gases to the refrigeration unit to prevent the precooling unit from becoming gas locked.

3. A method of treating crude oil to retain the natural volatile gases therein consisting in introducing oil to a dehydration unit for removing well water and other foreign matter therefrom, conveying the clean oil from the dehydration unit to a pre-cooling unit, conveying the oil from the pre-cooling unit to a refrigeration unit, conveying the oil from the bottom of the refrigeration unit to storage, bypassing gases liberated from said oil in advance of the pre-cooling unit to prevent the latter from becoming gas locked, and introducing the liberated gases into the top of the refrigeration unit to cause absorption thereof with the oil therein.

4. The process of treating oil which comprises passing the oil through a washing chamber, conducting the oil from said chamber through a pre-cooling chamber, passing the oil from the pre-cooling chamber through a refrigeration chamber, and conducting gases from the top of the washing chamber into the top of the refrigeration chamber.

5. In apparatus for treating oil, a washing chamber, a pre-cooling chamber connected with the washing chamber to receive the oil therefrom, a refrigerating chamber, a conduit for conducting the oil from the bottom of the cooling chamber into the top of the refrigerating chamber, and a conduit connecting the top of the washing chamber with the top of the refrigerating chamber for conducting gases from the former into the latter.

GUSTAV DE BRETEVILLE.
